UNITED STATES PATENT OFFICE.

JAMES F. LOWE, OF MILWAUKEE, WISCONSIN.

SHOE-LACE HOLDER.

1,413,859.

Specification of Letters Patent. Patented Apr. 25, 1922.

Application filed April 18, 1921. Serial No. 462,149.

To all whom it may concern:

Be it known that I, JAMES F. LOWE, a citizen of the United States, and a resident of Milwaukee, in the county of Milwaukee and State of Wisconsin, have invented a new and useful Improvement in Shoe-Lace Holders, of which the following is a full, clear, and exact description.

My invention relates to improvements in shoe lace holders, and it consists in the combinations, constructions, and arrangements herein described and claimed.

An object of my invention is to provide a shoe lace holder having means for engaging with the upper of a shoe and with the lace of a shoe, whereby the looped end portions of the shoe lace are securely maintained in adjusted position relative to the shoe and are not permitted to hang loosely from the knot in the lace.

A further object of my invention is to provide a device of the type described that can be quickly and easily applied to and removed from a shoe and when in operative position occasions no discomfort to the wearer of the shoe.

A further object of my invention is to provide a simple and inexpensive device of the type described that is thoroughly practical commercially.

Other objects and advantages will appear in the following specification and the novel features of the invention will be particularly pointed out in the appended claims.

My invention is illustrated in the accompanying drawings, forming part of this application, in which

Fig. 1 is a view showing the use and application of the device,

Fig. 2 is an enlarged section along the line 2—2 of Fig. 1,

Fig. 3 is a detail of a portion of the device,

Fig. 4 is a similar view of another portion of the device.

Considerable annoyance is ordinarily experienced by wearers of laced shoes on account of the ends of the shoe lace becoming entangled with various articles and frequently becoming untied. It sometimes happens that injury to the wearer is caused by a shoe lace having become fast in an obstruction, thereby tripping the wearer of the shoe. When the ends and loops of the shoe lace are tucked between the upper of the shoe and the leg of the wearer, as is

sometimes done, discomfort to the wearer results and the upper of the shoe is bulged in such a manner as to detrimentally affect the appearance of the same. When my improved shoe lace holder is used, the loops and ends of the shoe lace are held in adjusted position without discomfort to the wearer and with the appearance of the shoe enhanced rather than impaired.

In carrying out my invention, I provide two separable rocker members denoted generally at 1 and 2. These rocker members are formed of any suitable material, preferably of light metal, and have the general appearance illustrated in the drawings. It is to be noted that the rocker member 1 is bowed at 3 intermediate its length and that spaced apart coaxially alined bushing members 4 and 5 are carried by the bowed portion on the outside thereof. The rocker member 2 is provided with a cooperating bushing 6 carried on the outside of a bowed portion 7 and is adapted for disposition between the adjacent ends of the bushings 4 and 5 when the rocker members 1 and 2 are arranged relative to each other in the positions shown in Fig. 2. A pindle 8 is then projected through the registering bores of the bushings and secured therein in any suitable manner as by having its ends upset, whereby the rocker members 1 and 2 are hingedly connected together intermediate their ends.

The bowed portion 7 of the rocker member 2 continues in a reverse bow 9, thereby offsetting the end portion 10 of the rocker member 2 with respect to its other end portion 11.

The end portion 11 of the rocker member 2 is substantially parallel with a corresponding end portion 13 of the rocker member 1, while the other end portion 12 of the rocker member 1 is substantially parallel with the end portion 10. The end portions 11 and 13 are adapted to be grasped between the thumb and finger of a hand and obviously the end portions 10 and 12 will be moved apart when the rocker members 1 and 2 are rocked by pinching the end portions 11 and 13 together. The end portions 11 and 13 are normally maintained apart by a V-shaped spring 14 that is disposed therebetween and has parallel extensions 15 and 16 secured to the inner sides of the end portions 11 and 13 as at 17. The end portion 12 has a groove 18 in its inner wall adjacent the end thereof and the end portion 10 has a ridge 19

on its inner wall cooperating with the groove 18, whereby an upper of a shoe 20 is gripped when inserted between the end portions 10 and 12.

5 From the foregoing description of the various parts of the device, the operation thereof may be readily understood. The end portions 11 and 13 are grasped and pressed together against the tension of the spring 10 14. The loops 21 of a shoe lace 23 are then slipped over the end 10 of the rocker member 2 and moved between the end portions 10 and 12 until portions thereof are disposed within the bowed portion 9 of the 15 rocker member 2. The loops 21 are then passed over the end 11 of the rocker member 2 and will be maintained in the positions shown in the drawings when the end portions 10 and 12 are arranged to straddle 20 the upper of the shoe in adjusted position relative the edges thereof, the member 1 being placed between the upper of the shoe and the leg of the wearer. When the pressure of the fingers on the end portions 11 25 and 13 is relaxed, the upper of the shoe will be gripped between the end portions 10 and 12 on account of the tension of the spring 14.

It will be understood that the loops 21 30 will be formed so that the end portions 22 of the shoe lace are relatively short. Consequently, since the loops 21 are held in adjusted position, entanglement of the shoe lace with various articles is precluded.

35 I claim.

1. A device of the character described comprising two separable rocker members

hingedly connected intermediate their ends, and spring means disposed between said rocker members adjacent one end for clamping the opposite end portions thereof to opposite sides of a shoe upper and of portions of a shoe lace placed therebetween. 40

2. A device of the character described comprising two separable rocker members 45 arranged to face each other and hingedly connected intermediate their ends, said rocker members having their inner walls formed to provide cooperating gripping surfaces adjacent one end thereof, and spring means arranged between said rocker members at the opposite end thereof and tending to move the ends having the gripping surfaces together. 50

3. A device of the character described 55 comprising two separable rocker members, each being bowed laterally intermediate its ends, said rocker members having the bowed portions thereof hingedly connected and one of said rocker members being curved toward the opposite rocker member adjacent the point of hinged connection so that the end portions thereof lie in parallel planes and the corresponding end portions of the two rocker members can be moved into 60 parallel planes, and spring means disposed between said rocker members for maintaining the offset end portion of one rocker member and the corresponding end portion of the other rocker member in clamping engagement with the upper of a shoe and with adjacent portions of a lace of the shoe. 70

JAMES F. LOWE.
